[57] **CLAIM**

The ornamental design for a wall hook, as shown and described.

DESCRIPTION

FIG. 1 is a bottom, left, front isometric view of a first embodiment of a wall hook showing our new design;

FIG. 2 is a front elevational view of the wall hook illustrated in FIG. 1;

FIG. 3 is a rear elevational view of the wall hook illustrated in FIG. 1;

FIG. 4 is a right side elevational view of the wall hook illustrated in FIG. 1, the left side elevational view being the mirror image thereof;

FIG. 5 is a bottom plan view of the wall hook illustrated in FIG. 1;

FIG. 6 is a top plan view of the wall hook illustrated in FIG. 1;

FIG. 7 is a top, right, front isometric view of a second embodiment of a wall hook showing our new design;

FIG. 8 is a front elevational view of the wall hook illustrated in FIG. 7;

FIG. 9 is a rear elevational view of the wall hook illustrated in FIG. 7;

FIG. 10 is a left side elevational view of the wall hook illustrated in FIG. 7, the right side elevational view being the mirror image thereof;

FIG. 11 is a top plan view of the wall hook illustrated in FIG. 7; and,

FIG. 12 is a bottom plan view of the wall hook illustrated in FIG. 7.
